UNITED STATES PATENT OFFICE.

PAUL W. LEHMAN, OF MILWAUKEE, WISCONSIN, ASSIGNOR TO THE FISK RUBBER COMPANY, OF CHICOPEE FALLS, MASSACHUSETTS, A CORPORATION OF MASSACHUSETTS.

INNER-TUBE DEFULATOR.

Application filed August 5, 1926. Serial No. 127,468.

In the manufacture of inner tubes it is customary, after the tube is completed, to inflate and submerge the tube in a tank of water or otherwise subject it to a test to detect leaks.

After such operation it is necessary to completely deflate the tubes for further inspection and boxing. My invention relates to a device for deflating the tubes and has for its object to provide a device of that character which will deflate a substantial number of tubes at one time and so arranged as to facilitate the handling of the tubes to permit of a substantially continuous operation.

In the accompanying drawings which illustrate one embodiment of my invention,

Figure 1 is a side elevation,

Figure 2 is a plan view and

Figure 3 is a detail showing the manner of supporting the tubes during the deflating operation.

Referring to the drawings 1 indicates a substantially rectangular frame to which are secured stationary platens 2 and 3. The lower members 4 of frame 1 serve as tracks upon which a carriage 5, provided with wheels 6 is adapted to be reciprocated. Carriage 5 carries platens 8 and 9 adapted to cooperate respectively with stationary platens 2 and 3. Carriage 5 is reciprocated by means of an air cylinder 11, secured to uprights 12, forming part of frame 1, the piston rod 13 of the air cylinder is secured as at 14 to the carriage. The air connections and control valves for the air cylinder may be of any conventional form and have been omitted from the drawings.

The tubes 15 to be deflated are positioned on a rod 16 (see Figure 3) conveniently suspended from a carrier 17 running on an overhead track as indicated at 18. With the platens in the position as shown in Figure 1, a rod load of tubes is run between the open platens 2 and 8, as indicated in dotted lines at 20 in the latter figure, while a previous load of tubes as, at 21 is being deflated by 45 the pressure of platens 3 and 9. Reversal of the pressure in the air cylinder will reciprocate carriage 5 to close platens 2 and 8, deflating the tubes 20, at the same time opening platens 3 and 9 for the removal of deflated 50 tubes 21 and their replacement by another load of tubes. A substantially continuous operation is thus obtained with a minimum handling of the tubes.

I claim:

A device for deflating inner tubes which comprises two stationary platens, a carriage reciprocable between the stationary platens, a platen secured to each end of the carriage adapted to co-operate with the adjacent fixed 60 platen, all of said platens being supported so as to leave at least one side and the top edges thereof free for the admittance and ejection of a plurality of inner tubes having their valve stems above the upper edges of the platens, and means to reciprocate the carriage.

In testimony whereof I have signed my name to the above specification.

PAUL W. LEHMAN.
